UNITED STATES PATENT OFFICE.

JAMES D. WADE, OF GONZALES, TEXAS.

HYDRAULIC PUMPING JACK.

Application filed June 9, 1923. Serial No. 644,329.

To all whom it may concern:

Be it known that I, JAMES D. WADE, a citizen of the United States, residing at Gonzales, Gonzales County, Texas, have invented a certain new and useful Improvement in Hydraulic Pumping Jacks, of which the following is a full, clear, and exact description, such as will enable others skilled in the art to which it appertains to make and use the same.

My invention relates to fluid power operated jack to be used in pumping deep wells and has particular application to oil well operations.

Oil wells are ordinarily comparatively deep, often several thousand feet deep, and the head of liquid to be pumped is so great as to constitute a heavy load on the operating parts. The liquid, together with the weight of the rods and plunger, cause the plunger to be forced back, at the end of its upward stroke, with great force. Where the stroke is rapid and the length of stroke not properly timed, there is danger of jerking the pump rods excessively causing them to crystallize rapidly and break.

An object of my invention is to provide a pumping installation, the operation of which will cushion the force of the load on the down stroke of the rods and plunger, thus avoiding the danger of injury to the pump.

Another object is to provide a pumping apparatus which can be adjusted to operate with different lengths of stroke or at different speeds with equal efficiency and without vibration and damage to the pump rods.

Another object is to provide a hydraulically operated pump which may be readily adjusted for automatic regulation and wherein the parts are simple and strong and not easily damaged.

These and other objects and advantages, and the means whereby they are accomplished, will be set forth with particularity in the specification which follows:

Referring to the drawing herewith wherein like numerals of reference are applied to like parts in all the views, Fig. 1 is a side elevation partly in section showing the application of my invention to a pump; Fig. 2 is a similar side elevation taken at approximately right angles to the view shown in Fig. 1, the upper portion of the installation being broken away; Fig. 3 is a transverse section approximately on the line 3—3 of

Fig. 1 and Fig. 4 is a similar transverse section on the line 4—4 of Fig. 1.

My invention is shown as applied to the upper end of a casing 1, which projects downwardly into the well. The upper end of the casing is connected to a special head 2 which is threaded internally at its lower end for connection to the casing and is flared outwardly at its upper end to form a circular plate 3 upon which the pumping apparatus may be mounted. Formed in one side of the casing head 2 is a lateral opening 4 threaded for the attachment of a pipe 5 through which the fluid may find an outlet. The inner throat of the casing head 2 may be threaded as shown at 6 to receive a special nipple or bushing 7. This bushing is swaged inwardly at the upper end and provided with a stuffing box comprising a gland 8 which is adapted to compress the packing 9 within the upper end of the said bushing. This stuffing box is adapted to maintain a tight sliding fit about a polish rod 10 of ordinary construction. The upper end of the casing head 2 above the threaded throat 6 is tapered outwardly at 11 to provide a seat for slips of ordinary construction, to support the joints of the sucker rod while the rod is being inserted into or removed from the hole.

The pump operating means in my invention is actuated through a liquid, preferably oil, which is pumped into a series of cylinders in which the pistons operated thereby may serve to reciprocate the pump rod 10. In carrying out this idea I have provided a distribution chamber 12, made as shown in Fig. 4, of a U-shaped chamber having a central passage 13 therein communicating with three separate cylinders 14. The operating fluid is pumped into the chamber 13 through a lateral inlet pipe 15. This pipe connects with a two-way valve 16, said valve being operated by a lever 17, the governing of which will be later described. Fluid finding entrance to the valve through a supply pipe 18 may be directed through the pipe 15 to the compression chamber, or may, when the valve is properly turned, find a continuous passage back to the source of supply through a by-pass 19.

I contemplate employing a plurality of cylinders for the operation of the pump rod, and, as previously noted, three such cylinders are shown in the drawing. To provide

connection with these cylinders, the compression chamber 12 has three upwardly directed openings 20, which are internally threaded to connect with the cylinders 14 previously noted. These cylinders extend upwardly for a suitable distance, and I contemplate forming them from three to six feet long, although it is obvious they may be made of any desired length. The upper end 10 of each of the cylinders, as shown particularly in Fig. 1, is threaded externally for attachment to a stuffing box 21. This stuffing box has a packing 22 and an upwardly projecting cup-shaped receptacle 23 above the packing to provide a receptacle for oil to lubricate the piston during its operation.

The pistons 24 which operate in the cylinders 14 comprise solid rods which fit snugly within the said cylinders and extend 20 upwardly for a short distance above the same. At the upper end the pistons are attached rigidly to a yoke 25, the general shape of which is disclosed in Fig. 3. It comprises a spider with three radially projecting arms, at the ends of which are bearings 26 which are clamped about the reduced upper ends of the pistons by means of lateral plates on said bearings secured in place by means of clamping bolts 27. The upper 30 ends of the pistons are threaded, and the yoke, or spider, 25 is held firmly on said pistons by means of nuts 28.

There is a second lower yoke or spider 29, similar in construction to the yoke 25, and this yoke is shown particularly in Fig. 3. It has clamping plates 30 at the ends of the radial arms, said plates adapted to fit about the cylinders 14 and form a slidably connection therewith. The yoke or spider 29 40 is connected rigidly with the upper spider 25 by means of a plurality of rods 31, said rods being firmly connected at each end to the said yokes by means of nuts 32 thereon. These rods, as will be noted, serve to space 45 the two plates apart and to connect them rigidly together so that they will operate in unison. The lower plate only is connected to the pump rod and to accommodate said rod a lateral slot, 33 is formed in the side 50 of the yoke, extending inwardly to a central opening, 34, in which is received the upper end of the polish rod, 10, which rod is clamped rigidly in position in said opening by means of a clamping nut 35 on said rod.

55 The fluid which is pumped into the compression chamber 12 to force the pistons upwardly in the cylinders in an obvious manner, has an exit through the outlet pipe 36 at a point spaced somewhat from the inlet opening. Said pipe 36 has a valve 37 therein which is worked through a lever 38 thereon, which is adapted to be automatically operated by a valve gear, which will be later described.

85 The compression chamber and the pump-

ing apparatus connected therewith is rigidly secured to the base plate 3 by attaching lugs 39 on said chamber, which are adapted to register with similar lugs on said plate. Openings in the two cooperating parts are 70 adapted to register and to form an attachment by means of bolts 40 passing therethrough.

The automatic operation of the inlet and outlet valves 17 and 38 previously described, 75 is obtained through a special valve gear which is operated through the movement of the lower yoke or spider 29. As shown in Fig. 3, one of the clamping plates 30' at the outer end of one of the radial arms 29 is 80 formed with a laterally extending plate 41 thereon. This plate is formed integral with the outer plate 30', and has, on each end thereof, an outer opening 42 and an inner opening 43. There is, therefore, a pair of 85 openings at each end of the said plate 41, and said openings form a connection for operating valve rods which cooperate therewith. On the end of said plate, above the inlet valve 17, a rod 44 is slidably received within the outer opening 42 and an inner rod 45 is secured adjustably within the opening 43 by means of nuts 46, one on each side of said plate, said rod being threaded so that the length thereof may be regulated in an 90 obvious manner. The rod 44 is connected at its lower end 47 pivotally to one arm of the lever 17. Spaced upwardly from the lower end of said rod is a nut or block, 48, which is adjustable along the length of said rod and adapted to be fixed in position by set screw 49 on one side thereof. The upper end 50 of the rod is threaded and has a nut 51 thereon, which is adapted to be fixed in 95 adjusted position by set screw 52.

The valve rod 45 projects downwardly below the yoke and has formed thereon spaced below the upper end a valve operating means comprising a laterally projecting lug 53. A similar lug 54 is formed at the lower end, each of said lugs having a shoulder at the end thereof to contact with the arm 55 of the lever 17.

The operation of the outlet valve 38 is governed in the same manner as is the valve 17, and rod 56 is secured rigidly to the yoke and extends downwardly closely adjacent the end 57 of the lever 38, and has a valve operating member 58 below the upper end 115 similar in all respects to the operating member 53 of the rod 45. A second lug 65 is formed at the lower end of said rod. In the outer opening 42 above the valve 38 is a rod 59 which is slidable through said opening, and has a nut 60 adjustable thereon at 120 the upper end, and a nut 61 adjustable thereon at a point spaced above the lower end, and has the lower end pivotally hooked at 62 within the arm 63 of the lever 38.

125 The operation of this device may now be 130

understood. It is contemplated that the entrance of fluid through the pipe 18 may be governed as to quantity by means of a hand-operated valve, 67 shown therein, and the outlet of fluid through the pipe 36 beyond the valve 37 may also be regulated as to the rate of flow, by means of an ordinary hand-operated valve 68 therein. The fluid under pressure will then be forced in through the inlet pipe 18 and past the valve 16, into the compression chamber. The force of the fluid will carry the pistons upwardly to the end of their stroke. The operation of the valves will then automatically cause the release of pressure, allowing the pistons to drop and throw the weight of the apparatus and the load upon the plunger and pump rod. On the up stroke of the pistons and the lower yoke 29, the plate 41 will eventually contact with the upper nut 51 upon the rod 44, and by so doing throw the arm at 47 upwardly to a slight extent tending to partly close the inlet valve. At the moment the inlet valve is thus partly closed, the plate 41 will contact with the nut 60 on the valve rod 49. It will, however, only partially open said valve, allowing a slight amount of fluid to find an outlet through the valve. The regulation of the opening through the outlet pipe 36 by means of hand-operated valve 68 therein, will allow the fluid to go out at any desired rate. The load of the fluid in the well coming upon the yoke 29 will tend to cause the pistons and the pump rod to drop slowly, and this weight will be cushioned upon the liquid in the cylinders below the pistons. The descent of the yoke and rod 45 will bring the lower shoulder 54 against the arm 55 of the lever 17 and force it fully closed. As the yoke and pistons descend, the shoulder on the lower end of the block 65 on the rod 56 will contact with the outer end of the lever arm 57 on the valve 38, throwing it abruptly downward and opening the valve to its fullest extent, allowing the said block to pass downwardly beyond the lever arm. The fluid may then pass out through the outlet pipe 36 at the regulated rate of flow, and this rate may be adjusted so as to allow the pistons to be carried downwardly by gravity at the desired rate, according to the speed of operation desired in the particular pump to which the device is applied. It will also be obvious that adjusting the blocks 51 and 61 upon the rods 44 and 59 will serve to adjust the length of stroke in the manner desired.

When the downward stroke has been completed, the lower face of the plate 41 will contact with the nut 48 and throw the valve lever 17 to open the valve slightly and the same plate striking the nut 61 on rod 59 will tend to partially close the valve 37. The pistons will then start up and the lug 54 will strike the arm 55 and completely open

valve 16 to admit a full volume of fluid to the cylinders thus moving the pump rod upwardly to complete the upper stroke. The upward movement of the yoke 41 will bring the lug 58 against the arm 57 and close the outlet valve immediately on the commencement of the stroke upwardly. At the end of the upward stroke the valves will be again actuated to release the hydraulic pressure and allow the pistons and pump rod to drop as previously described.

This construction will be silent and powerful in its action and easily adjusted and controlled. The cushioning action of the fluid will remove all jar and vibration, thus eliminating a great source of wear.

The further objects and advantages of my device will be apparent to one skilled in the art.

What I claim as new and desire to protect by Letters Patent is:

1. An operating means for deep well reciprocating pump rods comprising a distributing chamber, a plurality of upright cylinders secured in said chamber, pistons in said cylinders, a pump rod yoke secured to said pistons; a valve controlled inlet for motive fluid to said chamber, a slowly operating valve controlled outlet therefrom and means secured to said pump rod yoke to control said valves simultaneously during the operation of the pistons.

2. An operating means for deep well reciprocating pump rods comprising, a distributing chamber, a plurality of vertically arranged cylinders connected with said chamber, pistons in said cylinders, a pump rod yoke secured to said pistons, valve-controlled inlet and outlet pipes for motive fluid connected with said chamber, and valve-governing rods on said pump rod yoke adapted to move the valves separately in said inlet and outlet pipes for the purpose described.

3. An operating means for reciprocating pump rods comprising, a distributing chamber, a plurality of cylinders connected therewith, a piston in each cylinder, upper and lower yokes connected with said pistons, inlet and outlet pipes connected with said chamber, valves in said inlet and outlet pipes and separate valve-control rods connected with said lower yoke and adapted to simultaneously operate said valves.

4. An operating means for reciprocating pump rods comprising, a compression chamber, cylinders connected therewith, pistons in said cylinders, connecting means between said pistons and the pump rod and automatically operated valves to admit fluid under pressure to said chamber and to permit it to exhaust in such manner as to cushion the down stroke of the pump rod in the manner described.

5. An operating means for reciprocating

pumps comprising, a cylinder, a piston therein, connecting means between said piston and said pump, automatic means to admit liquid under pressure to said cylinder, 5 and means to cut off said pressure liquid and allow it to exhaust at a predetermined rate, whereby the jar upon the pump is avoided.

6. An operating means for reciprocating 10 pumps comprising, a plurality of cylinders, pistons therein, means to admit liquid under pressure simultaneously to said cylinders, means to control the rate of admission of said liquid, and means to cut off said 15 liquid and to simultaneously allow it to exhaust at a predetermined rate.

7. An operating means for reciprocating 20 pumps comprising, a plurality of cylinders, pistons therein, a yoke connecting the upper ends of said pistons, a second yoke connected with said upper yoke and slidably on said pistons, inlet and outlet pipes leading to said cylinders, valves in said pipe, and a pair of valve control rods on said second 25 yoke for each of said valves whereby liquid under pressure may be admitted and exhausted therefrom at a predetermined rate.

8. In a pump operating means, a plurality of cylinders, pistons therein, hydraulic

means to raise and lower said pistons in 30 said cylinders at a predetermined rate and thereby prevent jar upon said pump and a pump rod operated by said pistons.

9. In a reciprocating pump, the combination of a casing head, a tapered seat in the 35 upper end thereof, a closure for said casing head comprising a threaded nipple having threaded connection with said casing head below said tapered seat, a stuffing box therein, a pump rod adapted to fit slidably in 40 said stuffing box and a plurality of hydraulically operated pistons connected with said pump rod above said stuffing box in the manner described.

10. In a reciprocating pump, the combination of a casing head, a tapered seat therein, a threaded connection below said seat, a nipple attached therein, a pump rod having a sliding fit with said nipple, a fluid compression chamber above said casing 50 head, cylinders connected therewith, hydraulically operated pistons in said cylinders and a connection between said piston and said pump rod.

In testimony whereof, I hereunto affix my 55 signature this the 2nd day of June, A. D. 1923.

JAMES D. WADE.
